James Wager. Troy, New York.
Letters Patent (Design No. 97) dated Oct 10th 1841

The schedule referred to in these Letters Patent and making part of the same. -

To all to whom these presents shall come:

Be it known, that I, James Wager, of Troy in the County of Rensselaer, and State of New York, have invented or produced a new design for Parlor Stone, and that the following is a full, clear, and exact description thereof, reference being had to the accompanying drawings, making part of this specification, which figure 1 is a perspective view of the stone, and figure 2, an elevation of the side plate.

My design consists of a Gothic pattern having clustered columns or pilasters projecting boldly at the corners; within these on the side there is a recess in imitation of a Gothic double headed window, within which is diamond shaped tracery centred with foliated ornaments, around the border are square dies with fleur de lis. The bases of the columns are embossed and around their centre they are bound by an oak leaf and acorn band. The moulding on top is surmounted by the top plate in outline a truncated pyramid of irregular shape and ornamented with foliage. Over each of the columns at the corners there is a low one also similarly embellished. This stone is surmounted by an elevated fluted water urn, as shown in figure 1, this gradually tapers towards the top, the base covering the most elevated part of the stone, and its summit terminates in a scroll and leaf ornament. What I claim as my invention and desire to secure by Letters Patent is the within described ornamental pattern designed for Stone
